UNITED STATES PATENT OFFICE

LUCILLE CHAMBERS AND JOHN CHARLES CHAMBERS, OF SAN FRANCISCO, CALIFORNIA.

ERASER CLEANING APPLIANCE

Application filed May 21, 1929. Serial No. 364,886.

This invention relates to office equipments in general and has more particular reference to a typewriter accessory which may be definitely entitled an eraser cleaner.

5 More precisely stated, we have developed a simple and economical device which may be conveniently used by typists, in conveniently cleaning and maintaining an eraser in good condition to promote clean work and to obviate the crude method of attempting to maintain the peripheral edge of the eraser clean by rubbing it on scratch paper, as is now the common method.

Briefly stated, the invention is carried into effect by provision of a simplified stand equipped with a rotary abrasive wheel especially constructed for cooperation with the eraser, said stand being further provided with conveniently operable means for holding the eraser in contact with the wheel while the eraser is being reconditioned.

The object and advantages derived from this novel contribution to the art will become more readily apparent from the following 25 description and drawings.

In the drawings:

Figure 1 is a side elevational view of the complete accessory showing the manner in which the eraser is held in place for cleaning.

30 Figure 2 is a front view of the same object observing the structure seen in Figure 1 in a direction from left to right.

Figure 3 is an enlarged fragmentary view in section and elevation showing the relationship and construction of parts more plainly.

Figure 4 is a top plan view of the eraser holding or retaining means.

Figure 5 is a top plan view of the eraser
40 spindle.

As seen in Figure 1 the reference character 6 designates generally a miniature stand having an appropriate attaching base 7 and a vertical standard 8. This standard is formed intermediate its ends with a horizontally elongated bearing 9, and above the bearing the upper end is bifurcated, the furcations being designated by the reference character 10. These furcations are apertured to accommodate a horizontal pivot bolt 11. Two parts

constituting a complete unit are fulcrumed or pivoted on this bolt. One part constitutes an arcuate arm 12 so shaped as to permit the free end portion 13 to be moved to a position to hold the eraser 14 in operative position. This portion 13 is shaped to provide a finger piece. On the under side of the arm is a grooved block 15 for cooperation with the edge of the eraser. This is of hard rubber made in the form of an abrasive. The arm 12 is provided adjacent its pivoted end with a keeper 16 in which the free end portion of the flat spring 17 is arranged. The opposite end of the spring is anchored as at 18 on the standard below the pivot. Mounted on the same pivot is a stub shaft 19 whose free end terminates in a spindle 20 over which the hub portion of the eraser is slipped.

A crank shaft 21 is mounted for rotation in the bearing 9. At one end is a shoulder forming collar 22 resting against the adjacent end of the bearing. Beyond this is a flat spaced portion 23 and then a reduced screw-threaded extremity 24 carrying a retaining nut 25 for the main rotary abrasive wheel 26. This wheel is formed with a peripheral groove 27 for reception of the eraser 14 as seen in the drawings. The opposite end portion of the shaft 21 is flat faced as at 28 and screw threaded at 29 to accomodate a retaining nut 30 for the crank handle 31. This permits the shaft 21 and its appurtenances to be rotated as a unit.

As before stated, the purpose of the invention is to clean a typewriter eraser, but it may be utilized to clean any other type of eraser for either pencil, ink, etc. The result may be accomplished thoroughly in a short space of time through the medium of an unusually simple device. In the block type of eraser it is understood that the finger pressed retaining device is not used. To accomplish this result simply hold the eraser on the main cleaner wheel and turn the crank handle. For the type of eraser shown in the drawings simply slip the eraser over the spindle and use the thumb attachment to bring the eraser into place. Then turn the handle with the right hand and regulate the cleaning process by pressure applied on the thumb 90

piece 13. Two turns will be sufficient to clean the eraser. Then take the thumb off of the retainer and the spring will pull the retainer to an out of the way position. The complementary lugs 32 and 33 on the pivoted ends of the parts 12 and 19 will cause them to move away from the roller 26 as a unit under the action of the flat spring 17.

This accessory it is believed is a novel and original contribution to the art, and is such as to fulfill the requirements of a device of this class, and in a highly satisfactory manner. The simplicity is such as to make it unnecessary to enter into a more detailed explanation.

Minor changes in shape, size, materials and rearrangement of details may be resorted to in actual practice so long as no departures are made from the accompanying claims.

Having thus described the invention, what we claim as new and desire to secure by Letters Patent is:—

1. As a new product of manufacture, an office accessory of the class described comprising a support, a shaft mounted for rotation on said support, a grooved abrasive wheel carried by said shaft, an arm pivotally mounted on the upper end of the support and adapted to swing over the wheel, a spring for moving the arm out of the way, said arm being formed with a finger piece and with a block having its groove for cooperation with the adjacent edge portion of the eraser, said block being adapted to be located in alignment with the peripheral portion of said wheel, together with a stub-shaft associated with said arm and adapted to be disposed in spaced parallelism with said first named shaft, said stub-shaft being provided with a terminal spindle for reception of the hub portion of the eraser.

2. As a new product of manufacture, an office accessory of the class described comprising a support, a shaft mounted for rotation on said support, a grooved abrasive wheel carried by said shaft, an arm pivotally mounted on the upper end of the support adapted to swing over the grooved periphery of said wheel, a spring for moving the arm to an out of the way position, said arm terminating in a finger grip and being provided with a block having a groove for cooperation with the adjacent edge portion of the eraser, said block being adapted to be located in alignment with the peripheral portion of said wheel, and means for supporting the eraser between the grooved portions of said wheel and block.

3. As a new product of manufacture, an office accessory of the character described comprising a rigid columnar support having a laterally projecting shaft mounted for rotation on said support and said shaft rotated by a crank, a grooved abrasive wheel carried by said shaft at the end opposite the

crank end of said shaft, an arm pivotally mounted at the upper end of the support and adapted to swing over the grooved periphery of said wheel, a contour conforming spring cooperating with the pivotally mounted arm at the upper end of the support for holding said arm out of operative position, said arm terminating in a finger grip and being provided with a block of abrasive material having a groove for cooperation with an adjacent edge portion of the eraser, said block being adapted to be located above and in alignment with the peripheral portion of said wheel, and means for supporting an eraser rotatably between the grooved portion of said wheel and the block.

4. As a new product of manufacture, an office accessory of the character described comprising a support, a shaft mounted for rotation on said support, a grooved abrasive wheel carried by said shaft, an arm pivotally mounted on the upper end of the support and adapted to swing over the wheel, a spring for moving the arm out of the way, said arm being formed with a finger piece and with a block having a groove for cooperation with the adjacent edge portion of the eraser, said block being adapted to be located in alignment with the peripheral portion of said wheel, together with a stub-shaft associated with said arm and adapted to be disposed in spaced parallelism with said first named shaft, said stub-shaft being provided with a terminal spindle for reception of the top portion of the eraser, said terminal spindle having a means for cooperation with the pivoted arm whereby said terminal spindle is caused to swing in unison with the upper arm when the said upper arm is moved in and out of position.

In testimony whereof we affix our signatures.

LUCILE CHAMBERS.

JOHN CHARLES CHAMBERS.
